Inventor

Henry Giese

By Doug & Hayes, Atty's.

UNITED STATES PATENT OFFICE.

HENRY GIESE, OF AMES, IOWA, ASSIGNOR TO IOWA STATE COLLEGE OF AGRICULTURE
AND MECHANIC ARTS, OF AMES, IOWA, A CORPORATION OF IOWA.

VENTILATOR.

Application filed April 28, 1926. Serial No. 105,193.

This invention relates to improvements in ventilators.

It is a well known fact that a certain amount of ventilation should always be provided for poultry when housed in a building, and at the same time the ventilation should be so established that excessive currents or drafts will be eliminated. It is, therefore, essential that a ventilator be provided with means whereby a small amount of ventilation will be provided after the temperature of the building has dropped below a predetermined amount, and after the temperature has been raised above a certain predetermined point a large amount of ventilation will then be necessary in order to prevent overheating of the building.

It is, therefore, the object of my invention to provide a ventilator having means for automatically controlling, to a certain extent, the ventilation of a building.

More specifically it is the object of my invention to provide a damper mechanism which may be easily and quickly mounted in ventilating flues of various sizes, and when so mounted the said damper mechanism will be automatically actuated through a certain predetermined temperature range, and will be locked in a partially closed position when the temperature falls below said predetermined temperature range, or locked in an open position when the temperature moves above the predetermined temperature range.

A further object is to provide a ventilating mechanism which is especially adapted to be used for ventilating poultry houses and the like.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a sectional view of a ventilating flue showing the manner in which my improved device is applied therein, a portion of the ventilating damper being cut away.

Figure 2 is a detail sectional view taken on the line 2—2 of Figure 1.

Figure 3 is a detail view of the damper

actuating mechanism which is shown partially in section.

55

Figure 4 is a detail perspective view taken on the line 4—4 of Figure 2.

Figure 5 is a detail sectional view taken on the line 5—5 of Figure 1.

The numeral 10 indicates the roof of a building such as a chicken house, in which is provided a ventilating opening 11, said opening having an upright ventilating flue 12.

Mounted within the flue 12 is my improved damper mechanism which comprises a shaft 13 pivotally mounted in suitable bearing members 14, said bearing members being secured to the inner surface of opposite side walls of the flue 12 by means of suitable screws or nails 15. Secured to the shaft 13 is a damper plate 16, said plate having a body portion 17 which is secured to the shaft 13 by means of a clamp 18. Said body portion 17 is provided with an opening 19 at its central portion and has one edge provided with a laterally extending portion 20, and the other edge provided with a laterally extending portion 21 extending in the opposite direction. Mounted on the shaft 13 in the opening 19 I have provided a pinion wheel 22 rigidly secured to said shaft.

Pivotally mounted on the shaft 13 is a pair of depending supports 23, the lower ends of which are designed to carry a thermostat 24. The lower end of the thermostat 24 is provided with a link 25 for the purpose of preventing oscillation of the thermostat, one end of the link being attached to the side member of the flue 12 by means of an eye bolt 26. The thermostat body 24 is provided with a contractile and expansible member 27, the upper end of which is provided with an upwardly extending yoke 28. The parts are so arranged that the shaft 13 extends through said yoke. It will be seen that as the member 27 expands and contracts, the yoke 28 will be elevated and lowered relative to the shaft 13.

100 One of the vertical parallel members of said yoke 28 is provided with an inwardly extending tooth 29 which is designed to make engagement with the pinion 22 and to impart rotary movement to said shaft 13 as 105 the said yoke is elevated or lowered, causing

the damper 16 to be moved from an open to a closed position, or vice versa. By this construction it will be seen that the yoke 28 is capable of movement after the tooth 29 has moved upwardly and disengaged the pinion 22, or is capable of further movement after disengaging the pinion on its downward movement, thereby providing means whereby the damper 16 may be actuated only through a certain predetermined temperature range. The said damper is unaffected by movement of the yoke when the temperature has varied either above or below said predetermined temperature range. The parts are so constructed and arranged that the damper 16 never moves to a position where the passage in the flue 12 is entirely closed. The dotted lines in Figure 2 shows the damper moved to a closed position, while the solid lines in said figure show the damper in its open position.

For locking the damper in either its open or closed position at such times when the pinion 22 is not engaged by the tooth 29, I have provided on the hub 30 of the pinion 22 an upwardly projecting arm 31 having on its inner face a lug 32 so arranged that when the said tooth 29 has moved upwardly and disengaged the pinion 22, the lug 32 will be rotated into alinement with the space between the inner edges of the flanges 33 of the yoke 28. The said lug 32 serves to prevent rotation of the arm 31 as the yoke 28 is elevated. The hub 30 is also provided with a downwardly extending arm 34 having an inwardly extending lug 35 which is also designed to pass between the flanges 33 when the said arm 34 has been moved to a vertical position by the downward movement of the yoke 28, and at the time the tooth 29 disengages the pinion 22, so that the said damper 16 is retained in its closed position as the said yoke 28 is lowered below the predetermined temperature range. One of the flanges 33 is made shorter than the other so that the ends of the longer one of said flanges will serve as stops to limit the inward movement of the lugs 31 and 35 and to aline said lugs with the space between the flanges. The arm 31 serves to lock the damper in an open position as the yoke is moved upwardly above the predetermined temperature range.

Thus it will be seen that I have provided a ventilating mechanism which may be easily and quickly applied to the interior of a ventilating flue, and when so applied will actuate the controlling damper through a certain predetermined temperature range, and any further variation of the damper controlling mechanism will be ineffective, as far as the operation of said damper is concerned, thus providing means whereby the damper may be moved to a partially closed position when the temperature has reached the lower limit of the predetermined temperature range.

and will be locked in the said closed position, providing means whereby the building will be insured of a certain amount of ventilation, sufficient to keep the building supplied with the proper amount of fresh air. 70

It will be seen that after the temperature has reached the upper limit of the predetermined temperature range, the damper will be moved to an open position and locked therein, permitting the maximum amount of 75 ventilation for cooling the building.

One of the advantages of my improved mechanism lies in the fact that the damper controlling mechanism is of a very compact form, which may be entirely assembled in 80 the factory and which may be easily and quickly applied to a ventilator flue by securing the bearing members 14 in position by means of the screws 15 and mounting the link 25, which in actual practice is simply a 85 small rod or wire which may be easily and quickly cut in the desired length, in the eye bolt 26.

I claim as my invention:

1. In combination, a building having an 90 upright ventilating flue, a damper for opening and closing said flue, a temperature controlled mechanism, means actuated by said temperature controlled mechanism for moving said damper from a partially closed position to an open position, or vice versa, through a certain predetermined temperature range, means for locking said damper in its open position at times when the temperature rises above said predetermined 95 temperature range and for locking said damper in its partially closed position at times when the temperature falls below said predetermined temperature range. 100

2. A ventilating device comprising a rotatively mounted shaft, a damper rigidly secured to said shaft having a central opening, a thermostat pivotally mounted to said shaft and depending through said opening, a pinion gear secured to the central portion of said shaft, a yoke member operatively connected with said thermostat and adapted to move transversely relative to said shaft and said pinion, said yoke being provided with a tooth designed to engage said pinion and to impart rotary movement to said shaft during a portion of the movement of said yoke, and means for locking said shaft against rotary movement at such times when the tooth is out of engagement with said pinion. 110 115 120

3. A ventilating device comprising a rotatively mounted shaft, a damper rigidly secured to said shaft having a central opening, a thermostat pivotally mounted to said shaft and depending through said opening, a pinion gear secured to the central portion of said shaft, a yoke member operatively connected with said thermostat and adapted to move transversely relative to said shaft and 125 130

said pinion, said yoke being provided with a tooth designed to engage said pinion and to impart rotary movement to said shaft during a portion of the movement of said yoke, means for locking said shaft against rotary movement at such times when the tooth is out of engagement with said pinion, and means for detachably and pivotally mounting said shaft within a ventilating flue.

4. A ventilating device having a ventilating opening, means for closing said ventilat-

ing opening, means for actuating said closing means as the temperature varies between two predetermined points, means for retaining said closing means in an open position when the temperature rises above said predetermined points, and means for retaining said closing means in a closed position when the temperature falls below said predetermined points.

Des Moines, Iowa, January 21, 1926.

HENRY GIESE.
